UNITED STATES PATENT OFFICE.

FRANK E. MARCY, OF SALT LAKE CITY, UTAH.

BATTY-MARCY.

1,080,768.

Specification of Letters Patent. Patented Dec. 9, 1913.

Application filed February 23, 1913. Serial No. 753,592.

To all whom it may concern:

Be it known that I, FRANK E. MARCY, citizen of the United States, residing at Salt Lake City, in the county of Salt Lake and State of Utah, have invented certain new and useful Improvements in Ball-Mills, of which the following is a full, clear, and exact description, reference being had to the accompanying drawings, forming a part hereof.

My invention has relation to improvements in ball mills or equivalent crushing and disintegrating apparatus wherein the material is reduced to particles of the desired size by means of Danish pebbles or steel balls or equivalent freely movable crushing bodies acting by impact and attrition upon the charge temporarily confined within a suitable tumbling barrel, tube, vessel, drum, or equivalent container, usually rotated about a fixed axis, the opposite ends or heads of the barrel being respectively provided with intake and discharge openings for the material, as understood in the art.

The object of my present invention is to construct an ore-crusher or mill with a view of securing a uniform size product; one which will automatically segregate the fines from the coarse particles, causing the former to advance or migrate toward the point of discharge of the mill; one which shall be economical; one eminently adapted for the crushing of ores where the final product shall neither be too fine nor too coarse and shall be of uniform grade for purposes of subsequent concentration; one treating a maximum charge in a minimum amount of time; one which shall be simple, comparatively cheap to construct, durable, and one possessing further and other advantages better apparent from a detailed description of the invention which is as follows:

In the drawings, Figure 1 is a side elevation of my improved mill; Fig. 2 is a middle vertical longitudinal section of the tube or cylindrical container of the mill, showing in side elevation one form of sorting drum or member to which my invention is in the main, directed; Fig. 3 is a horizontal sectional detail illustrating one method of securing to the tube the sections of which the sorting member is composed; Fig. 4 is a transverse vertical section on the line 4-4 of Fig. 2 looking toward the right, the illus-

tration of the ore contents in the mill being confined however to the plane on which the section is taken; Fig. 5 is a vertical cross section on the line 5-5 of Fig. 2, the illustration of the contents being likewise confined to the plane of the section; Fig. 6 is a vertical cross-section on the line 6-6 of Fig. 2; Fig. 7 is a vertical cross-section on the line 7-7 of Fig. 2 showing a projection of the entire ore-body when looking to the right in said figure; and Fig. 8 is a sectional detail on the order of the right hand end of Fig. 2, showing a modified form of sorting member.

Referring to the drawings, and for the present to Figs. 1 to 7 inclusive, 1 represents a tube, or cylindrical container or tumbling barrel provided with a lining of silex, hard gray iron or equivalent layer 2, the ends of the tube being closed by the heads 3, 4, secured to the cylinder in any proper mechanical manner as by flanges *a* overlapping the cylinder walls and riveted thereto. The container is provided at one end (in the present form shown) disposed about the flange of the head 3) with a gear-ring 5 meshing with a pinion 6 at one end of a shaft 7 mounted in suitable bearings on top of the blocks 8, 8, the shaft being provided with a drive-pulley 85 P over which passes a belt B leading to any suitable source of power (not shown). The head 3 (identified with the feed end of the mill) is provided with a hollow trunnion 9 the opening of which (approximately 16 inches diameter) is sufficient to allow a man to crawl into the mill when necessary for any desired purpose. The opposite head 4 is provided with a hollow trunnion 10 of smaller diameter, the trunnions being disposed symmetrically about the axis of rotation of the tube and supported in suitable bearings on top of the standards S, S. The ore is delivered to the mill through the opening of the trunnion 9 which serves as 100 the intake, from a hopper H, here shown conventionally and the ground or fine particles discharged from the mill through the trunnion 10 are caught in a launder or equivalent receptacle L only a portion of 105 which is shown in the drawing. The launder L may be a screening launder so that any oversize can be returned to the mill. It is of course only conventionally illustrated in the drawings. From the connections described it will be seen that with a 110 rotation of the shaft 7, the tube 1 will ro-

tate about its axis and its ore and pebble contents will be tumbled about. The balls or crushing bodies are represented by the reference letter *b* and the ore or charge proper by the letter *m*, the fines or granular particles representing the final product of the mill and ready to be discharged therefrom, being represented by *m'*. The segregation of the fine from the coarse particles and their automatic migration toward the discharge end of the mill during the grinding and tumbling operation, is accomplished by what I term a sorting "drum" or column 11 the drawings illustrating two forms of construction of the drum. This drum is located within the crushing compartment of the mill, being symmetrically disposed about the rotation axis of the mill and occupies a position adjacent the discharge-head 4. In the main form this sorting drum or member is composed of several sections (four in the present illustration) collectively forming when assembled a hollow truncated cone, the base of the cone resting in an annular groove *e* formed for its reception in the terminal wall *h* of a cylindrical platform 12 cast with the head 4 and disposed about the axis of the trunnion 10, the walls of the member 12 being provided with oblong openings *O* for the free passage therethrough of the material discharged from the mill. Stretched across the annular space between the base of the sorting member 11 and the end of the tube 1 is a wire-mesh screen or sieve 13 (about 20 mesh) the opposite edges of said annular screen being secured to the tube wall, and to the base of the sorting member respectively, in any convenient or suitable mechanical manner. The several sections of the sorting drum are preferably secured in position by means of bolts 14 passed respectively through lugs 15 on the drum sections, through the wall *h* and through the head 4, the nuts *n* being on the outside whereby the parts may at any time be tightened. The member 11 is further supported by a central tubular brace or strut 16 bearing with its free end against the converging ends of the several sections of the sorting drum, the fixed end of the brace being screwed into a central boss 17 formed on the wall *h* of the platform 12. By the arrangement just described it will be seen that the securing means for the sorting member are out of the way of the mill contents and thus do not in any way interfere with the free movement of the materials in the mill.

The operation of the mill can be best described in connection with the illustration in Fig. 2 to which reference will be made. In this figure, the tube 1 is rotating clockwise (if we look toward the right) that is to say, the upper portion is revolving toward the observer and the bottom portion from the observer. As stated at the outset, in order that there may be perfect grinding or crushing there must be a constant migration of the ore particles from the feed toward the discharge end, the particle first entering the mill being the first to leave the mill. Without the sorting member 11 or its equivalent there is no assurance that the particles will leave in the order in which they enter the mill and so a uniform (granular) product is practically impossible. Where water is resorted to to effect the migration aforesaid, such migration will be imparted only to the very finest slimes, but in the ordinary standard sliming mill that is fifteen feet long and half full of pebbles and ore there would be very little velocity of the water through the pebbles, and the carrying power of the current is very small. With the use of the sorting member 11 the pebbles will be higher at one end of the mill than at the other, and as the mill revolves there results a leveling action and a consequent migration, the material migrating consisting of pebbles and ore (coarse and fine). It is a well known fact that if we dump a mine car of ore or mine waste over a dump, the big rocks all rattle at the bottom and the fines remain by the tracks. So in my mill, if we cause a migration of the particles and have them higher at one end than at the other, the fines tend to remain at the high end and close to the discharge opening, the coarser particles gravitating to lower planes or levels. In this way a perfect separation of granular particles from the rest of the ore and pebbles is made possible. The presence of the sorting member 11 therefore has the effect of raising the pebbles to a higher level at one end (the discharge end) than at the other, such raising causing a higher pressure of the pebbles in that particular zone. In addition to that, the rolling action of the pebbles and their movement is no longer around an axis parallel to the axis of rotation of the mill itself, but the pebbles tend to roll and grind and revolve about axes at various angles to the axis of the mill. Along the immediate planes of section indicated by section lines 4-4, 7-7, in Fig. 2, and in fact in the zone between the head 3 and the adjacent terminal of the member 11, the ore and pebbles assume a position represented by the material in Fig. 4. In the zone in the region of the plane of section indicated by section line 5-5, the material disposes itself substantially as shown in Fig. 5. Near the point of discharge and in the zone in the region of the section line 6-6, the material disposes itself substantially as shown in Fig. 6, Fig. 7 representing the projection of the entire body of ore to the right of section line 7-7, so that the ore which is disposed along the plane of the section line 7-7 proper is merged with the body of ore beyond the sec-

tion. In Fig. 2, the arrow K_1 shows the direction of the falling pebbles and ore in the cylindrical part of the mill; the curved arrows K_2 , K_3 , K_4 , K_5 , show the direction the pebbles and ore are taking behind the sorting drum or member 11; and the curved arrows K_6 and K_7 show the direction of the pebbles and ore underneath the sorting drum and that portion which is readily visible. This crowding action around the sorting drum is very effective even in the treatment of original blocks of ore, in lieu of ore and pebbles. The arrows K_2 to K_7 inclusive show the general trend of the material around the sorting drum 11, and obviously describe paths about axes more or less inclined to the axis of rotation of the mill with which the axis of the sorting drum is coincident. The combined effect of the mill's rotation and the disposition of peripheral surface of the walls of the sorting drum not only causes the material to creep upward toward the base of the sorting drum, but the inclined surfaces of the drum cause the pebbles and coarse particles to gravitate toward the zone in the vicinity of the section lines 4-4, and 7-7, the fines remaining at the base of the drum where they are crowded through the screen 13 and thence pass through the openings O of the platform 12, whence they enter the hollow trunnion 10 and discharge into the launder L. The general trend or longitudinal migration of the particles is from the feed end 9 toward the discharge end 10, such trend being an axial one. On the other hand there is a return migration or counter trend of the coarse particles and pebbles toward the apex of the conical or tapering sorting drum, which counter trend does not disturb the fines, these being left to pass through the screen 13 (which prevents any coarse particles not returned into the mill, from passing into the trunnion 10). In the zone between the head 3 and the tip of the member 11, and notably in the zone defined by the planes of section indicated by the lines 4-4, 7-7, it may be said that the particles in the main tumble in vertical planes, the longitudinal or axial migration being mostly confined between the limits of the opposite ends of the sorting drum 11. Of course as fresh ore is fed in from the hopper it takes the place of that which has "migrated" out of the mill and the grinding action is continuous.

In Fig. 8 I show a hollow conical sorting drum 11, the base of which is secured to the head 4' of the tube or cylinder 1, the trunnion 10' being cast integral with said head. In this modification the discharge openings C' are formed at the bottom of the peripheral walls of the drum and there is no provision for a screen. Other forms will suggest themselves to the skilled mechanic. The sorting drum need not necessarily be

conical or frusto-conical in the geometric sense of these terms, any equivalent form being contemplated by my invention. It may be stated however that as the form of the drum approaches a cylinder, its sorting action diminishes, so that it is desirable to have a fair degree of taper or convergence given to its peripheral walls. By making the drum hollow the weight thereof is materially reduced as must be obvious to the skilled mechanic. A solid drum however, with suitable provision to allow for the escape of the fines would fall within the scope of my invention.

Having described my invention, what I so claim is:—

1. In combination with a tumbling-barrel or container rotatable about an axis and having a crushing compartment provided with intake and discharge openings disposed about said axis, a member having walls converging toward the intake opening and terminating substantially within the crushing compartment for segregating the fine from the coarse particles and operating to effect a migration of the fines toward the discharge opening.

2. In combination with a tumbling-barrel rotatable about an axis and having a crushing compartment provided with intake and discharge openings disposed about said axis, a member having walls converging toward the intake opening and terminating at each end in the crushing compartment, for segregating the fine particles from the coarse particles, and operating to effect a migration of the fines toward the discharge opening and a counter migration of the coarse particles away from said discharge opening.

3. In combination with a tumbling-barrel rotatable about an axis and having a crushing compartment provided with intake and discharge means at respectively opposite ends of the barrel, a sorting member disposed about the rotation axis and having peripherally continuous walls terminating at each end within the crushing compartment, said walls converging from the discharge toward the intake end of the compartment, and operating to segregate the fine from the coarse particles and effect a migration of the fines toward the discharge end.

4. In a tumbling vessel rotatable about a fixed axis and provided with a crushing compartment, a sorting member having its terminals in said compartment and having tapering peripherally continuous walls traversed by the material between said terminals, and operating to impart to the material during its traverse along said walls and while being crushed, motions about independent axes inclined to the axis of rotation of the vessel.

5. In combination with a tubular vessel

- rotating about its axis and provided with a crushing compartment having respectively intake and discharge openings located at opposite ends of the vessel, a sorting member 5 disposed about said axis and terminating within the crushing compartment, said member having peripheral walls operating to cause a migration of the fines toward the discharge opening while the material is being 10 crushed, the walls of the sorting member converging from the discharge toward the intake end of the vessel, whereby the coarse particles are caused to migrate away from the discharge end.
- 15 6. In combination with a tubular vessel rotating about its axis and provided with intake and discharge openings for the material at opposite ends of the axis, a sorting member disposed about said axis and positioned adjacent the discharge opening and spaced from the inner walls of the vessel, the walls of the sorting member converging from the discharge toward the intake end of the vessel, and operating to segregate the 20 fines from the coarse particles and direct such fines toward the discharge opening.
7. In combination with a tubular axially rotatable tumbling vessel provided with terminal heads having central intake and discharge openings respectively, a sorting drum disposed about the rotation axis of the vessel adjacent the discharge head thereof, the walls of the drum converging from said discharge head toward the axis of the vessel, and spaced from the inner walls of the vessel, means for establishing intercommunication 25 between the discharge opening and the space between the drum and inner walls of the vessel, the drum operating to segregate the fines from the coarse particles and cause a migration of said fines toward the discharge opening, and a flow thereof through 30 said intercommunicating means into the discharge opening, and a screen interposed in the path of flow of said fines.
8. In combination with a tumbling barrel having a head provided with a central discharge opening, a platform surrounding said opening and provided with peripheral openings for the flow of the fines therethrough, a sorting drum secured to said platform and having walls tapering away from said discharge opening and operating to cause a migration of the fines toward the openings of the platform.
9. In combination with a tumbling barrel having a head provided with a central discharge means, a hollow platform on said head located in the barrel and provided with peripheral openings for the flow of the fines therethrough to the discharge means, a sorting drum on the platform having walls tapering away from said discharge means, and a screen disposed about the base of the drum and interposed between the latter and the walls of the barrel.
10. In combination with a tumbling barrel having a head provided with a central discharge means, a hollow platform on said head located in the barrel and provided with peripheral openings for the flow of the fines therethrough to the discharge means, a sorting drum on the platform having walls tapering away from said discharge means, and a screen disposed about the base of the drum and interposed between the latter and the walls of the barrel.
- In testimony whereof I affix my signature, 85 in presence of two witnesses.
